UNITED STATES PATENT OFFICE.

ETHAN H. EARLE, OF POMONA, CALIFORNIA, ASSIGNOR OF ONE-HALF TO GEORGE R. E. MILLIGAN, OF LOS ANGELES, CALIFORNIA.

AEROPLANE.

1,419,363.

Specification of Letters Patent. Patented June 13, 1922.

Application filed June 7, 1920. Serial No. 397,098.

To all whom it may concern:

Be it known that I, ETHAN H. EARLE, a citizen of the United States, residing at Pomona, in the county of Los Angeles and State of California, have invented a new and useful Aeroplane, of which the following is a specification.

This invention relates to an aeroplane adapted to fly in a manner similar to aeroplanes at present in use, and also adapted to ascend and descend in a circle whose axis lies within the aeroplane, near the forward end of the fuselage.

An object of the invention is to give to an aeroplane a circular ascending and descending motion similar to that obtained with a helicopter, so that the aeroplane can take flight from and alight within a comparatively small area without an extended run and so that climbing and descent can be easily effected.

Another object of the invention is to make provision for elevating or depressing of the tail and simultaneously effecting turning of the tail to the right or left by operation of tilting horizontal planes.

Other objects and advantages will appear hereinafter.

The accompanying drawings illustrate the invention.

Figure 1 is a plan view of an aeroplane built in accordance with the provisions of this invention.

Fig. 2 is a front elevation of Fig. 1.

Fig. 3 is an enlarged sectional elevation on line indicated by x^3-x^3 , Fig. 1.

Fig. 4 is an enlarged elevation from line x^4-x^4 , Fig. 1 of the control for operating the propeller blade angle-changing mechanism.

Fig. 5 is an enlarged fragmental sectional elevation on line indicated by x^5-x^5 Fig. 6.

Fig. 6 is a side elevation of the aeroplane from the left of Figs. 1 and 2.

Fig. 7 is a perspective view of one end of the wings, showing the control for the aileron.

Fig. 8 is an enlarged plan view of one of the propellers and its angle-changing mechanism, the forward bearing of the engine and a portion of the engine also being shown.

Fig. 9 is an elevation mainly in vertical section on line indicated by x^9-x^9 , Fig. 8.

Fig. 10 is an elevation partly in section on

the irregular line indicated by $x^{10}-x^{10}$, 55 Fig. 8.

There is provided a fuselage 1 having a suitable landing gear, in this instance said gear comprising a front frame 2 provided with ground wheels 3, and said gear also 60 comprising a castor wheel 4 and its swiveling bracket 5. The forward end of the fuselage 1 forms a pilot's cockpit 6 and connected with said forward end are upper and lower wings 7, 8. In this instance the invention 65 is shown in the drawings as being embodied in a biplane, but it is to be understood that it can just as well be embodied in a monoplane or in a type of machine having more than two planes.

Mounted on opposite sides of the cockpit between the wings 7, 8 are motors 9, the shafts of which are indicated at 10. The shafts project forwardly beyond the leading edges of the wings and are provided with 70 propellers 11. In this particular instance the propellers are mounted in substantially the same positions occupied by the tractor propellers commonly in use, but it is to be understood that, if desired, the propellers may be 75 positioned rearwardly of the wings after the manner obtaining in the pusher type of aeroplane.

In order to accomplish one of the principle objects of the invention, means are provided to change the angle of the propeller blades, and the construction is such that the blades may be rotated substantially 80° about their longitudinal axes so that either propeller can be operated as a tractor type 90 or as a pusher type. The propellers and their angle-adjusting mechanisms are alike and therefore but one of the propellers and the angle-changing mechanism therefor will be described in detail as follows: The 95 propeller blades 12 are mounted at opposite ends of a shaft 13 adapted to oscillate in bearings 14 of a U-shape propeller carrier 15 which is fixed to the outer end of the motor shaft 10, the forward bearing for said shaft 100 being indicated at 16.

Keyed or otherwise fastened to the shaft 13 is a hub 17 having an arm 18 which is pivoted at 19 to a rod 20. The rod 20 is pivoted at 21 to a collar 22 shiftably 105 mounted on the engine shaft 10. In order to shift the collar 22 it is provided with an annular groove 23 engaged by a shift-

ing ring 24, the collar 22 having a running fit in the ring. The ring 24 is pivoted at 25 to upper and lower bell crank levers 26 which are pivoted at 27 to a bracket 28 5 carried by the bearing 16. One of the levers 26, in this instance the upper one, is pivoted at 29 to an operating member 30 which, in turn is connected at 31 to an operating lever 32 that is pivoted at 33 to 10 a bracket 34 mounted on the wall 35 of the cockpit. The bracket 34 is provided with a toothed quadrant 36 selectively engaged by a detent 37 movably mounted on the lever 32. The lever 32 may thus be 15 held in different positions so that the propeller will operate either to pull or push that side of the aeroplane with which the propeller is associated.

The wings 7, 8 may be of any construction and shape suitable for proper operation of the aeroplane and no attempt with some exceptions is made in the drawings to give in detail the construction of the wings, the wings are slightly convex on their under 25 surfaces and substantially flat on their upper faces and the fore and aft edges are alike and since such construction is well understood in the art to which the invention pertains. However, I at present deem it 30 preferable to incline the wings upwardly toward their tips as clearly shown in Fig. 2 so as to aid in proper balance in flight. The upper wing 7 includes movable surfaces indicated at 38 near its outer ends for 35 the purpose of changing the angle of incidence of said surfaces for producing a lifting or depressing effect on the wing according to the positions to which the movable surfaces are adjusted. In the present instance the movable surfaces 38 are in the 40 form of ailerons hinged at 39 to the wing. Tilting mechanisms 40 are provided for controlling the ailerons, but said mechanisms are of any well known or preferred 45 type and therefore need not be described in detail herein.

The fuselage 1 is provided at its rear end with a fixed horizontal tail plane 41, the rear edges 42 of said plane being aslant forwardly and outwardly. In this instance the edges 42 extend substantially at angles of 50 45° to the longitudinal axis of the fixed tail plane. Hinged at 43 to the plane 41 and extending outwardly from the edges 55 42 thereof are tilting tail planes 44 which are operated by tilting mechanisms indicated in general by the character 45. In this instance each tilting mechanism 45 comprises arms 46, 47 projecting from the 60 upper and lower surfaces, respectively, of the tilting plane and to said arms are fastened control lines 48, 49, respectively. The lines 48, 49 engage pulleys 50 fastened to the plane 41 and may be connected to any 65 suitable control member such, for example,

as those ordinarily employed for controlling the rudder and elevator of an aeroplane of the usual construction.

To operate the aeroplane, assuming that it is at rest upon the earth, the pilot will 70 adjust the blades of one of the propellers so that the blades thereof will drive the air rearwardly and he will adjust the blades of the other propeller so that the blades thereof will drive the air forwardly, thus 75 turning the aeroplane about an axis that lies substantially midway between the tips of the wings, or substantially within the cockpit. As the aeroplane rotates in this manner the tail describes a circle and the 80 castor wheel 4 follows and supports the tail. As the aeroplane rotates the forward edges of the wing portions on one side constitute the leading edges and the rear edges of the wing portions on the other side 85 constitute the leading edges on that side. The wings with their ailerons, thus, in effect, function like the horizontal propeller of a helicopter.

When the aeroplane reaches a speed of 90 rotation deemed by the pilot to be sufficient to cause the aeroplane to rise from the earth the pilot will depress that aileron adjacent the edge of the wing functioning at the time as the following edge, and he 95 will raise or tilt upwardly that aileron adjacent the edge of the wing functioning at the time as the leading edge. For example, if the aeroplane be assumed to be rotating clockwise in Fig. 1, the aileron on the pilot's 100 left will be depressed and that on his right will be elevated. The aileron thus adjusted will catch the air in such manner as to cause the wings to rise in a small spiral. Still assuming, for purposes of description, that 105 the aeroplane is rotating clockwise in Fig. 1, the tail plane 44 at the leading edge of the tail will be elevated and that at the following edge of the tail will be depressed, and these planes thus adjusted will catch 110 the air in such manner as to cause the fuselage to rise on substantially an even keel.

After the aeroplane has risen to any altitude desired by the aviator, if he desires to fly forwardly he will adjust that propeller which at the time is acting as a pusher, so that it will function as a tractor the same as the other propeller. This adjustment may be effected quickly, or it may be effected slowly so that the aeroplane will 115 gradually slow in its spinning or rotary movement. As the turning momentum decreases the aeroplane flies in ever widening circles due, at first, to the loss of turning power of the propeller of which the blades 120 are being adjusted from pusher position toward neutral position, and due thereafter to the increasing pull of said propeller as its blades are being adjusted from neutral to 125 tractor or pull position. The tendency of 130

the slowing side of the machine is to sink, and this tendency may be counteracted as much as desired by appropriate adjustment of either or both of the ailerons. After an interval of time, owing to both propellers functioning as tractors, the aeroplane will advance in a straightaway course.

In the forward flight of the aeroplane steering to right or left, and flying to higher or lower altitudes may be effected by operating the various controls in a manner well understood in the art to which the invention pertains. It is clear that turning of the aeroplane to the right or left may also be effected by changing the angle of the blades of the appropriate propeller. If, for example, the right propeller blades be adjusted to decrease the pull, then the right end of the wings will be driven at less speed than the left end.

To cause the aeroplane to descend in a circle whose diameter is approximately no greater than the wing spread, adjustments in reverse order to those described for ascending will be effected by the pilot. It is clear that to dive both tail planes 44 will be depressed, thus raising the tail of the machine. When it is desired to fly upwardly, the tail planes 44 will be elevated, thus de-

pressing the tail.

It is to be understood that, though I have set forth in detail a construction for effecting adjustment of the propeller blades to different angles, the invention in its broader phases contemplates the use of any suitable mechanical contrivance for effecting reversal

of the pitch of the propeller blades and maintaining of said blades in the different adjusted positions.

The foregoing described construction of the tail of the aeroplane, though cooperatively related to the reversible propeller blades, may be employed with advantage in aeroplanes which, otherwise, are of any well known or preferred construction since the planes 44 may be operated simultaneously to effect vertical steering and singly to effect or aid in horizontal steering.

I claim:

In an aeroplane, the combination of a wing, propellers at opposite sides of the longitudinal axis of the aeroplane, the plane of rotation of the propellers being normal to the path of flight, means to rotate the propellers, means to turn the blades of one of the propellers about their longitudinal axes to positions the reverse of the blades of the other propeller to cause rotation of the wing in a horizontal plane as a helicopter, said wing having movable surfaces adjacent its ends, and means to adjust the movable surfaces to increase or diminish the angles of incidence of said surfaces while the wing is rotating to cause the aeroplane to rise or descend in circular flight.

Signed at Los Angeles, California, this 28th day of May, 1920.

ETHAN H. EARLE.
